DEMODULATION OF TIME-MODULATED ELECTRICAL PULSES

Maurice Moise Levy, London, England, assignor, by mesne assignments, to International Standard Electric Corporation, New York, N. Y., a corporation of Delaware

Application May 30, 1944, Serial No. 538,062
In Great Britain June 1, 1943

13 Claims. (Cl. 250—27)

1

The present invention relates to arrangements for receiving and demodulating electric pulse trains which are phase-modulated in accordance with a signal wave.

By phase-modulated pulse trains are to be understood those in which the time interval between successive pulses is varied according to the signal, the duration of each individual pulse being constant. By the method of the invention, an auxiliary train of pulses is derived from the phase-modulated train by means which combines each pulse with the preceding pulse delayed by a constant time slightly larger or smaller than the repetition period. The derived train is then applied to charge a condenser, the potential of which then varies according to the amplitude of the modulating signal, as will be demonstrated. The potential of the condenser may be applied to an amplifier from which the signal may be obtained in the usual way.

According to the invention, there is provided an arrangement for demodulating a phase modulated train of short electrical pulses comprising means for obtaining from the said train a delayed train of which each pulse overlaps in time the following pulse of the original train, means for combining each pair of overlapping pulses in order to derive a train of pulses whose durations vary in accordance with the modulating signal wave, and means for extracting the said signal wave from the derived train of pulses.

The invention will be described with reference to the accompanying drawings in which:

Figs. 1, 2 and 4 give diagrams used in explaining the principles of the invention;

Figs. 3 and 3a show schematic diagrams of two embodiments; and

Fig. 5 shows a schematic diagram of an arrangement for lengthening the pulses before demodulation.

In Fig. 1 sketch *a* shows three successive pulses from a radiated train of regularly repeated short pulses assumed to be of rectangular outline. The pulses really consist of short packets or bundles of radio frequency oscillations of rectangular form. Sketch *b* shows diagrammatically what may occur when the pulse train is phase-modulated. The *n*th pulse is supposed not to be affected, so that the two *n*th pulses in sketches *a* and *b* occur at the same time. In *b*, however, the (*n*+1)th pulse is shown as arriving slightly earlier than usual, while the (*n*+2)th pulse is a little late. Thus the interval between the *n*th and (*n*+1)th pulses is reduced by the modulation and that between the (*n*+1)th and (*n*+2)th

2

pulses is increased. It will, of course, be understood that the modulation may make any pulse late or early by any amount.

Fig. 2 shows at 1 a sinusoidal wave component of a modulating signal, the frequency being $\omega/2\pi$. The solid vertical lines 2 represent the centre lines of the pulses of an unmodulated train, the period, or time interval between successive pulses, being t_0 , which will, of course, be small compared with the period $2\pi/\omega$ of the signal wave. The duration of the pulses will furthermore be small compared with t_0 . The dotted vertical lines 3 represent the centre lines of the pulses as they would be displaced by the modulating signal represented by the curve 1. The pulses which coincide with the points where the wave 1 cuts the time axis are unaffected, but the others are advanced or retarded proportionally to the amplitude of the wave 1 at the times of occurrence of the pulses. The pulses thus behave rather like a condensation wave in a fluid medium.

According to the invention, the modulated pulses 3 are received on the aerial of a radio receiver RR, Fig. 3, and the pulse outlines are derived in an appropriate detector D which is connected to a delay network DN, which preferably comprises an artificial non-dissipative transmission line. The output terminals of DN are connected to a resistance R_1 which should be equal to the characteristic impedance of the network in order to avoid reflections at the output terminals.

A thermionic valve V of any suitable type has two control grids G_1 and G_2 , one of which is connected to the input of the network DN, and the other to an intermediate point by an adjustable tap. The two control grids are biassed by means of a battery B through high resistances R_2 and R_3 (or they may be biassed in any other convenient way), and the anode is connected to the high tension supply through a condenser C shunted by a resistance R.

Referring now to Fig. 4, sketch *a* shows four of the phase-modulated pulses after detection, which are drawn so that the spacing progressively decreases. These pulses should be of positive polarity and are applied to the grid G_1 . The grid G_2 is connected at a point in the network DN such that any pulse reaches it after a delay T_0 which is a little greater than t_0 . Curve *b* in Fig. 4 shows how the pulses are applied to G_2 . It will be seen that the *n*th delayed pulse overlaps the (*n*+1)th original pulse, and the

($n+1$)th delayed pulse overlaps the ($n+2$)th original pulse, and so on.

The grids G_1 and G_2 should be negatively biased so that the anode current is cut off except during those periods when both grids have a pulse applied. Accordingly, the anode current of the valve V will vary in the manner shown in sketch c of Fig. 4, which represents a series of derived rectangular pulses, of which the n th is obtained by combining the n th delayed pulse with the ($n+1$)th original pulse, and so on.

If desired, as shown in Fig. 3a, the grid G_2 may be omitted (together with R_3 and the tapping connection to DN). R_1 is removed, the output terminals of DN being left open. The original pulses are then reflected at the output terminals and re-appear at the input terminals as delayed pulses. If the length of the network DN is such as to correspond to a delay of $T_0/2$ then the same derived pulses c of Fig. 4 are obtained. The grid G_1 should in this case be biased so that the anode current is cut off except when two pulses are simultaneously applied to the grid. Alternatively, the valve may be biased as a normal amplifier so that when the original and delayed pulses are applied the anode current varies in the manner indicated in Fig. 4, sketch d . By following the valve V with another suitably biased valve (not shown), the wide lower part of the combined pulse may be cut away leaving only the narrow upper part which will be the derived pulse desired.

The manner in which the demodulation of the pulses is obtained by the arrangement of Fig. 3 is most easily understood from a mathematical analysis.

Let t be the time when the n th unmodulated pulse is received. Then $t=t_c+nt_0$, where t_c is a constant time which is determined by the time origin chosen. Since $\omega/2\pi$ is the frequency of the signal wave I (Fig. 2), the amplitude of this wave at time t will be proportional to $\sin \omega t$ and the time displacement of the n th pulse from its unmodulated position in time will therefore be $a \sin \omega t$, where a is a parameter which depends on the depth of modulation.

Thus the time t_n when the n th modulated pulse appears will be given by

$$t_n = t - a \sin \omega t \\ = t_c + nt_0 - a \sin [\omega nt_0 + \omega t_c]$$

Similarly the time $t_{(n+1)}$ corresponding to the ($n+1$)th modulated pulse is given by

$$t_{(n+1)} = t_c + (n+1)t_0 - a \sin [\omega t_0(n+1) + \omega t_c]$$

Thus

$$t_{(n+1)} - t_n \\ = t_0 - 2a \sin \frac{1}{2} \omega t_0 \cos \frac{1}{2} [\omega t_0(2n+1) + 2\omega t_c]$$

As already stated, t_0 will be small compared with $2\pi/\omega$, so that $\frac{1}{2}\omega t_0$ will be a very small angle. Hence, approximately,

$$t_{(n+1)} - t_n = t_0 - a\omega t_0 \cos [\omega nt_0 + \omega(t_c + t_0/2)] \quad 1$$

Let P be the duration of each of the pulses of the modulated train (sketch a , Fig. 4), and let p_n be the duration of the n th derived pulse (sketch c , Fig. 4), then

$$p_n = P + t_{(n+1)} - t_n - T_0 \quad 2$$

If the pulse train had been unmodulated, all the derived pulses would have had the same duration $p = P + t_0 - T_0$ (obtained from Equations 1 and 2 by putting $a=0$).

Thus $p_n = p - a\omega t_0 \cos (\omega nt_0 + \beta)$, in which β has been written for $\omega(t_c + t_0/2)$.

If i is the amplitude of the anode current pulses in the valve V , and if these pulses are applied to charge a condenser C , then the condenser will be raised by n pulses to a potential

$$E = \frac{i}{C} \sum_{n=1}^n p_n \\ = \frac{i}{C} \left[np - a\omega t_0 \sum_{n=1}^n \cos (\omega nt_0 + \beta) \right]$$

Since t_0 is small compared with $2\pi/\omega$, it will be regarded as an infinitesimal quantity dt . The time of occurrence t of the n th unmodulated pulse will be taken as the time variable. It has already been stated that $t = t_c + nt_0$, so that $\omega nt_0 + \beta = \omega t + \omega t_0/2$.

Thus approximately

$$E = \frac{i}{C} [np - a\omega \int \cos (\omega t + \omega t_0/2) dt] \\ = \frac{i}{C} [np - a \sin \omega t]$$

neglecting the small phase angle $\omega t_0/2$.

25 The potential of the condenser thus has a component

$$\frac{inp}{C}$$

30 which steadily increases, and also another component

$$\frac{ia}{C} \sin \omega t$$

35 which is proportional to the original modulating signal voltage. The first component is effectively removed by shunting the condenser C by the resistance R (Fig. 3) which provides a leak which limits the rise of potential across the condenser.

40 Thus the potential variation across the condenser C corresponds to the original modulating signal, and may be filtered if necessary to remove traces of the pulses and amplified by any suitable arrangement (not shown).

45 It should be pointed out that T_0 could have been chosen to be a little less instead of a little greater than t_0 . Similar derived pulses c (Fig. 4) would be obtained. To should not, however, be made equal to t_0 , for then the derived pulses would not distinguish the positive and negative loops of the modulating signal.

It has been assumed that the duration P is at least equal to twice the maximum time displacement of any pulse product by the phase modulation.

55 If this were not so certain of the derived pulses would disappear altogether. This requirement will usually be met, but if not, the received pulses may be lengthened before demodulation by any method, for example in the manner shown

60 in Fig. 5. The pulses to be lengthened are applied to the input terminals IN of a delay network DN terminated at the other end by a resistance R_s equal to its characteristic impedance. Any number of valves $V_1, V_2 \dots V_n$ have their anodes connected together, and their control grids are connected respectively to intermediate tapping points along the network. The anodes are supplied with current from the high tension source through a common resistance A_1 and are connected through a blocking condenser C_1 to the control grid of a collector valve CV supplied with anode current through another resistance A_2 . The output is taken from the anode of CV through a blocking condenser C_2 , and the usual grid resistance G is shown. The valves V_1 to V_n should be

appropriately biased below the cut-off by any convenient means (not shown).

The control grids of the valves V_1 to V_n are tapped at points such that the pulses applied at the terminals IN reach these points after successive intervals a little shorter than the duration P of each pulse, so that the valves V_1 to V_n are unblocked in turn, each remaining unblocked until just after the next has become unblocked.

The valve CV should be biased so that a moderate anode current flows, but so that when any one of the valves V_1 to V_n is unblocked, the corresponding fall in anode potential takes the control grid of CV below the cut-off. Thus CV will be blocked until the pulse has travelled past the last valve V_n . Thus inverted pulses having a duration a little less than nP will be obtained at the terminals OUT.

The number of the valves V_1 to V_n may be halved if the resistance R_S is removed, leaving the output terminals of the delay network open. The pulses will then be reflected at the open end and will return to the input end, unblocking each of the valves a second time. The distance from the control grid of V_n to the open end should correspond to a delay a little less than $P/2$, and care should be taken to see that the input terminals of the delay network are terminated with its characteristic impedance in order to avoid multiple reflections.

It will be understood that when it is desired to lengthen the original pulses before demodulation, the circuit of Fig. 5 is interposed between the detector D and the delay network DN (Fig. 3), the terminals IN being connected to D and the terminals OUT to DN.

Fig. 3 which has been described above, gives one embodiment of the invention, which however, may be carried out in other ways. Although the preferred form of the delay network DN is a non-dissipative transmission line, any type of network which will delay the pulses by the required amount can be used. Moreover, any suitable arrangement may be used for combining the original and delayed pulses.

What is claimed is:

1. A source of a train of short phase-modulated electrical pulses of substantially constant duration and an arrangement for demodulating said phase modulated train of short electrical pulses comprising delay means for obtaining from the said train a delayed train of which each pulse overlaps in time the following pulse of the original train, the delay being of a value differing from the unmodulated time spacing of the pulses of said train by a predetermined amount, means for combining each pair of overlapping pulses thus producing a train of pulses whose durations vary in accordance with the modulating signal wave, and means for extracting the said signal wave from the derived train of pulses.

2. An arrangement according to claim 1, in which means is provided for applying the original and delayed trains of pulses simultaneously to a mixing valve from the anode circuit of which the derived pulses are obtained.

3. An arrangement according to claim 1 in which means is provided for applying the original and delayed trains of pulses simultaneously to a mixing valve, and means for blocking said valve except when at least two pulses are simultaneously applied thereto.

4. An arrangement according to claim 1 in which the delay means comprises a valve having two control grids one of which is connected to an

input terminal of the delay means, and the other to an intermediate point thereof, the output terminals of the delay means being connected to a resistance equal to its characteristic impedance.

5. A source of a train of short phase-modulated electrical pulses of substantially constant duration and an arrangement for demodulating said phase-modulated train of short electrical pulses comprising delay means for obtaining from the said train a delayed train of which each pulse overlaps in time the following pulse of the original train, the delay being of a value differing from the unmodulated time spacing of the pulses of said train by a predetermined amount, means for combining each pair of overlapping pulses thus producing a train of pulses whose durations vary in accordance with the modulating signal wave, and means for extracting the said signal wave from the derived train of pulses comprising a condenser adapted to be charged by the pulses of the derived train so that its potential varies in accordance with the modulating signal wave.

6. The arrangement according to claim 5 and in which the condenser is shunted by a resistance.

7. The arrangement according to claim 5 and in which the means for combining is a valve having grids to which the original and delayed pulses are applied, and an anode circuit comprising said condenser.

8. An arrangement for demodulating a phase modulated train of short electrical pulses, comprising means for lengthening the duration of pulses, means for obtaining from the train of lengthened pulses a delayed train of which each pulse overlaps in time the following pulse of the original lengthened pulse train, means for combining each pair of overlapping pulses thus producing a train of pulses whose durations vary in accordance with the modulating signal wave, and means for extracting the said signal wave from the derived train of pulses.

9. The arrangement according to claim 8, and in which the means for lengthening comprises a delay network.

10. The arrangement according to claim 8, and in which the means for lengthening comprises a plurality of normally blocked valves and means for unblocking them in succession by the pulses received.

11. The arrangement according to claim 8 and in which the means for lengthening the pulses comprises a delay network to which the pulse train is applied, a plurality of normally blocked valves having control grids connected to different points of said network between which the delay is less than the time duration of the pulses, whereby said pulses reach them after intervals shorter than said duration unblocking said valves in turn, each remaining unblocked until just after the next has become unblocked, anodes for said valves connected in multiple, a collector valve having a control grid connected with said anodes, means for blocking the collector valve until the pulse has travelled past the last of said valves, an output circuit for the collector valve in which pulses are obtained which are inverted with respect to those applied to the network, and whose duration is less than said certain duration multiplied by the number of said valves.

12. An arrangement for effectively lengthening the pulses of a train of electrical pulses having a certain duration, comprising a delay network to which the pulse train is applied, a plurality of normally blocked valves having control grids connected to different points of said network between

75

which the delay is less than the time duration of the pulses, whereby said pulses reach them after intervals shorter than said duration unblocking said valves in turn, each remaining unblocked until just after the next has become unblocked, anodes for said valves connected in multiple, a collector valve having a control grid connected with said anodes, means for blocking the collector valve until the pulse has travelled past the last of said valves, an output circuit for the collector valve in which pulses are obtained which are inverted with respect to those applied to the network, and whose duration is less than said certain duration multiplied by the number of said valves.

13. An arrangement for effectively lengthening the pulses of a train of electrical pulses having a certain duration, comprising a delay network having input terminals for the pulse train, a resistance in which said network terminates equal to its characteristic impedance, a plurality of valves, each biassed below its cut-off, said valves having control grids connected to different intermediate points of said network between which the delay is less than the time duration of the pulses, whereby said pulses reach them after intervals shorter than said duration to unblock said valves in turn, each valve remaining unblocked until just after the next has become unblocked, anodes for said valves connected in multiple, a source of potential, a resistance over which said source is connected with said anodes, a collector valve

having a control grid connected with said anodes, said collector valve having also an anode connected with said source, a blocking condenser in the grid and a second resistance in the anode connection of the collector valve, means for biasing the collector valve to permit the flow of some anode current but to place its grid below the cut-off when any of said valves is unblocked, said collector valve remaining blocked until the pulse has travelled past the last of said valves, an output circuit for the collector valve in which pulses are obtained which are inverted with respect to those applied to the network, and whose duration is less than said certain duration multiplied by the number of said valves.
